UNITED STATES PATENT OFFICE

160,953

CAPTIVE BALL GAME BOARD

Joseph A. Mettler, Indianapolis, Ind.

Application October 12, 1948, Serial No. 149,078

Term of patent 3½ years

(Cl. D34—5)

to all whom it may concern:

Be it known that I, Joseph A. Mettler, a citizen of the United States, residing at Indianapolis, in the county of Marion and State of Indiana, have invented a new, original, and ornamental Design for a Captive Ball Game Board, of which the following is a specification, reference being had to the accompanying drawing, forming part there-

Fig. 1 is a top plan view of a captive ball game board, showing my new design; Fig. 2 is an end elevational view thereof; and Fig. 3 is a perspective view thereof.

I claim:

The ornamental design for a captive ball game board, as shown.

JOSEPH A. METTLER.
